UNITED STATES PATENT OFFICE.

LEON W. SIMMONS, OF FOREST LAKE, MINNESOTA.

ENVELOP.

No. 913,987.

Specification of Letters Patent.

Patented March 2, 1909.

Application filed May 20, 1908. Serial No. 433,960.

To all whom it may concern:

Be it known that I, LEON W. SIMMONS, a citizen of the United States, residing at Forest Lake, in the county of Washington, State 5 of Minnesota, have invented certain new and useful Improvements in Envelops; and I do hereby declare the following to be a full, clear, and exact description of the invention, such as will enable others skilled in the art 10 to which it appertains to make and use the same.

This invention relates to envelopes, more particularly to the class of envelopes so constructed that they cannot be opened surreptitiously or opened without detection, and has for one of its objects to improve the construction and increase the efficiency and utility of devices of this character.

With these and other objects in view the 20 invention consists first in providing the end flaps of an envelop with projecting tongues adapted to fold over the sealing flap after the latter is folded and sealed, and thus firmly secure the sealing flap and prevent it from 25 being opened without destroying the tongues, and thus revealing the fact that the envelop has been tampered with.

The invention further consists in providing the end flaps of an envelop with clefts where- 30 by tongues are released which are foldable over the sealing flap after the latter is closed.

With these and other objects in view the invention consists in certain novel features of construction as hereafter shown and de- 35 scribed and then specifically pointed out in the claim, and in the drawings illustrating the preferred embodiment of the invention, Figure 1 is a view of an envelop from the sealing side with the sealing flap in open position and the tongues folded back to permit the sealing flap to be disposed upon the upper edges of the end flaps and over the terminals of the back flap. Fig. 2 is a view of the envelop in closed position with the tongues 40 folded over and sealed upon the closure flap. Fig. 3 is a section on the line 3—3 of Fig. 2. Fig. 4 is a view of the blank from which the envelop is constructed.

The improved device may be applied to 50 any of the various forms of envelopes, but for the purpose of illustration is shown applied to a conventional envelop formed from a body 10, end flaps 11—12, a back flap 13, and

a closure flap 14, of the usual construction, the end flaps having clefts 15—16 whereby 55 tongues 17—18 are released, the clefts being so disposed relative to the closure flap 14 that when the latter is closed with its gummed edge 19 disposed over the free edges of the end flaps and over the point of the back flap, 60 the "root" portions of the tongues will come at the lower portions of the closure flap, so that the tongues can be readily folded over the adjacent edges of the closure flap, as shown, and thus complete the "sealing" of 65 the envelop. The tongues will be provided with adhesive material which enables them to be sealed upon the closure flap, as will be obvious. By this simple means the envelop is doubly secured after the ordinary sealing 70 of the closure flap is accomplished, so that the envelop cannot be opened surreptitiously without exposing the fact of such opening, so that the contents of the envelop are protected from unlawful access, as will be ob- 75 vious.

The device is simple in construction, does not add materially to the expense of the envelop, and does not add to its weight or size, as nothing is added to or taken from the envelop, the only change being to form the clefts in the end flaps which can be done without additional expense when the envelop is manufactured.

The improved device may be applied to 85 envelopes of all sizes and to envelopes manufactured from different kinds of paper, and will be found very effective especially in sending matter which it is desired to protect from surreptitious handling.

What is claimed, is:—

An envelop comprising a front, a sealing flap extending from said front and having converging outer edges, end flaps foldable over the front, a bottom flap foldable over 95 the front and adjacent portions of the end flaps, said end flaps having slits parallel to the converging edges of the sealing flap and bearing over the same when the sealing flap is in closed position.

In testimony whereof, I affix my signature, in presence of two witnesses.

LEON W. SIMMONS.

Witnesses:

A. F. WALKER,
CHAS. YONNGEN.
